Isidor Dresdner,
By his attorney,
Philip J. O'Reilly.

UNITED STATES PATENT OFFICE.

ISIDOR DRESDNER, OF BROOKLYN, NEW YORK.

PLUCKING-MACHINE.

SPECIFICATION forming part of Letters Patent No. 605,311, dated June 7, 1898.

Application filed December 24, 1897. Serial No. 663,297. (No model.)

To all whom it may concern:

Be it known that I, ISIDOR DRESDNER, a citizen of the United States, residing at Brooklyn, county of Kings, and State of New York, have invented a new and useful Fur-Plucking Machine, of which the following is a specification, reference being had to the accompanying drawings, forming part of the same.

My invention has for its object to provide a machine that will be free from any tendency to pluck out the fur from a skin along with the long hair thereof while the said skin is undergoing treatment for the removal of the latter.

15 In the accompanying drawings, Figure 1 is a top view of a fur-plucking machine constructed according to my invention. Fig. 2 is a side elevation of the same. Fig. 3 is a front elevation of certain parts thereof. Fig. 20 4 is an enlarged section on the line $\alpha\alpha$, Fig. 1; and Fig. 5 is a longitudinal section of one of the rollers comprised in the machine.

a designates a bed-plate upon which are erected standards b b' b'', containing bearings for a main shaft c, having a fast and a loose pulley c' c'' secured thereon.

Secured to the shaft c by means of set-screws is a bladed roller d, consisting of two collar portions d', between which extend arms 30 d'', preferably four in number, to which blades d''' are secured. These blades are formed with a concave recess along their outer edges, in which are placed rods of elastic material d⁴.

A covering d⁵ of suitable material, preferably 35 thin and flexible sheet metal, such as tin, encloses the rods d⁴ and blades d³, and each blade, with its cover, is rigidly secured to an arm d² by means of screws d⁶.

If desired, the blades d³ may be dispensed 40 with and the properly-formed outer edges of the arms d² be employed in place thereof; but I prefer the construction described.

e is a belt of any suitable elastic material, with which the blades d³ coöperate. It is supported by a series of rollers arranged in such 45 a manner that the blades d³ when rotating will come in contact with said belt e and roll therewith with a gradually-increasing-pressure contact between them, beginning with a 50 very light pressure, sufficient to engage the hairs and not injure or hold the fur, and in-

creasing as the rolling continues until the pressure is sufficient to grasp the hairs tightly enough to pluck them out. Preferably this belt is of rubber or other elastic material 55 faced both inside and outside with leather cemented or otherwise secured to said elastic material.

As here shown, there are three rollers e' e² e³, around which the belt e is moved intermittently by the rotation of the blades d³. The roller e' is arranged above the shaft c in a perpendicular line therewith. The roller e² is arranged more nearly adjacent to the blades d³ than the roller e', so that as the 60 blades d³ rotate they will engage the belt e and then compress it gradually from the time they are in line with the roller e' until they are in line with the roller e². The roller e³ is arranged to support the upper portion of 65 the belt and is provided with collars e⁸ to retain the belt in position. The rollers e' and e² are carried by standards f of a vertically-adjustable frame f'. The roller e³ is carried in arms f¹⁰, pivotally connected to the standards f by screws f¹¹, upon which the arms may be turned to adjust the position of the roller e³ for tightening the belt e. After 70 proper adjustment the arms are locked in position by the screws f¹¹. Each of these three 75 rollers comprises an inner tube e⁴, secured to its supports by set-screws, and an outer tube or sleeve e⁵ to rotate on the inner tube between said supports.

The inner tubes have closed ends to serve 80 as oil-reservoirs and are provided with oil-feed holes e⁶ and outlet-holes e⁷. In this manner the sleeves e⁵ are kept constantly lubricated and by reason of their length and protected arrangement are rendered very durable 85 and effective for high speed.

The standards f extend rearwardly and downwardly through supports a', erected upon the bed-plate a, and are rigidly secured to a cross-bar f². This cross-bar f² is pivotally connected to a lever f³, fulcrumed at f⁴ and having its free end connected by a link f⁵ to a foot-lever f⁶, fulcrumed at f⁷.

f⁸ are coil-springs to support the standards in their proper normal position, which may 90 be adjusted by nuts f⁹. By means of this foot-lever I am enabled to readily and tem-

porarily apply increased pressure to compensate for any inequality in the nature of the skins undergoing treatment.

5 *g* is a plate bent substantially as shown and is rigidly secured to the standards *b' b*². Its upper straight edge is in close proximity to the blades *d*³ and serves, chiefly, to protect the hands of the operator and aid somewhat in preventing the fur portion of the skin from 10 being drawn in between the belt and blades.

15 *h* is a vertically-adjustable arm connected to a support *h'*, forming part of a slide-carriage *h*². This carriage comprises two rods *h*³ *h*³, working in bearings *h*⁴ and having at their front ends a cross-bar *h*⁵ secured thereto. By this arrangement the skins may be inserted from the side around the free end of the arm *h*, thus affording means for handling them with facility and expedition. Arms *h*⁶ are secured to the rods *h*³ and have their lower ends mounted to slide on stationary rods *h*⁷, secured to the frame of the machine.

20 *h*⁸ *h*⁹ are stops to limit the to-and-fro motion of the carriage *h*².

25 *i* is a spring secured to the frame of the machine and serving to move back the carriage *h*² against the stops *h*⁸.

j is a roller journaled in suitable bearings attached to the arm *h*.

30 *k* An ordinary pneumatic exhaust-pipe *k* may be arranged in the rear of the blades *d*³ and belt *e* to carry off the plucked-out hairs.

35 In operation both ends of the skin are grasped by the hands of the operator and inserted between the supporting-roller *j* and the bladed roller. The carriage *h*² is then pushed toward the machine by the body of the operator pressing against the cross-bar *h*⁵. The operator then draws the skin upwardly and 40 downwardly over the roller *j*, during which time the long projecting hair portions of the skin will be lifted up by the upward motion of the rotary blades and be seized between the belt *e* and the rotary blades with sufficient 45 pressure to pluck them out, while the fur portion of the skin will be unaffected, as before described.

I claim—

1. The combination of a bladed roller, a belt of elastic material which is moved intermittently by the rotation of the blades of said roller, and rollers supporting the said belt and arranged to cause the said blades to bear against the belt with a gradually-increasing pressure during the time they roll in contact together, substantially as described.

2. The combination of a bladed roller, a belt of elastic material which is moved in-

termittently by the rotation of the blades of said roller, and rollers supporting the said belt, one of said rollers being arranged above the shaft of the bladed roller in a perpendicular line therewith, and another of said rollers being arranged in closer proximity to the blades than the latter, whereby as the blades 65 rotate they will engage the belt and compress it gradually from the time they are in line with the first-mentioned roller until they are in line with the last-mentioned roller, substantially as described.

3. The combination of a bladed roller, an elastic belt and rollers supporting the same, said rollers comprising an inner perforated tubular oil-receptacle secured by set-screws in supports and an outer sleeve fitted to rotate on the said inner tube between the sides of the supports, one of said rollers being adjustable toward or from the other rollers and provided with collars to tighten and retain the belt in position, substantially as described.

4. In combination, a bed-plate, standards erected thereon, a bladed roller mounted in said standards; an elastic belt supported by rollers and coöperating with said bladed roller; vertically-adjustable standards for carrying the belt-supporting rollers, secured in bearings formed in the bed-plate and united by a cross-bar; springs controlled by stop-nuts to press the standards upwardly; a foot-lever adapted to move the same downwardly, 90 and a supporting-roller for the skin mounted in an arm secured to one side of a sliding carriage and open to admit skins sidewise around its free end, substantially as described.

5. In combination, a bladed roller, an elastic belt coöperating with said roller, a carriage comprising two slide-rods united by a cross-bar and working in fixed bearings; arms secured to said slide-rods and adapted to slide on stationary rods provided with adjustable stops; a spring to move the carriage in one direction, and a skin-supporting roller mounted on the free end of an arm secured to one of the said slide-rods, substantially as described.

6. A bladed roller consisting of two collar portions between which extend arms to which blades are secured, said blades being formed with a concave recess along their outer edges in which are placed rods of elastic material 110 inclosed by a flexible cover, substantially as described.

ISIDOR DRESDNER.
